CONNECTOR FOR ROPE, LINE OR SIMILAR ARTICLE

James Earl Weiss, 1494 Howe Road, Kent, Ohio

Filed Apr. 11, 1972, Ser. No. 243,115

Term of patent 14 years

Int. Cl. D30—80

U.S. Cl. D30—27

FIG. 1

FIG. 2

FIG. 3

FIG. 4

FIG. 1 is a perspective view of a connector for rope, line or similar article illustrating one embodiment;

FIG. 2 is a plan view of the article of FIG. 1;

FIG. 3 is an elevational view of the right side of the article in FIGS. 1 and 2; and

FIG. 4 is a plan view illustrating another embodiment of the invention.

I claim:

The ornamental design for a connector for rope, line or similar article, substantially as shown and described.
